(57) CLAIM

The ornamental design for mouse with cord wrap, as shown and described.

DESCRIPTION

FIG. 1 is a perspective view of a mouse with cord wrap showing our new design with the cord wrapped in position; FIG. 2 is a perspective view thereof, showing the cord unwrapped and broken away to indicate indeterminate length;

FIG. 3 is a top plan view thereof;

FIG. 4 is a left side elevational view, the right side elevational view being a mirror image thereof;

FIG. 5 is a bottom plan view thereof.

FIG. 6 is a front elevational view thereof; and,

FIG. 7 is a rear elevational view thereof.

The broken lines shown in FIGS. 1, 2, 3, 4 and 6 are for illustrative purposes only and form no part of the claimed design.
